H. MEREDITH-JONES.
STARTING MECHANISM FOR EXPLOSIVE ENGINES.
APPLICATION FILED JUNE 24, 1912.

1,071,775.

Patented Sept. 2, 1913.

UNITED STATES PATENT OFFICE.

HUBERT MEREDITH-JONES, OF NEW YORK, N. Y., ASSIGNOR TO COLUMBIA NUT AND BOLT COMPANY, INCORPORATED, OF BRIDGEPORT, CONNECTICUT, A CORPORATION OF NEW YORK.

STARTING MECHANISM FOR EXPLOSIVE-ENGINES.

1,071,775.

Specification of Letters Patent.

Patented Sept. 2, 1913.

Application filed June 24, 1912. Serial No. 705,418.

To all whom it may concern:

Be it known that I, HUBERT MEREDITH-JONES, a subject of the King of England, residing at New York city, county of New York, State of New York, have invented an Improvement in Starting Mechanism for Explosive-Engines, of which the following is a specification.

This invention has for its object to provide a simple, inexpensive, effective and easily operated starting mechanism for explosive engines that will avoid the objections to the various mechanisms of this character that have heretofore been produced.

With these and other objects in view the invention consists in the novel constructions and combinations of the parts which I will now describe referring to the accompanying drawing forming a part of this specification and using reference characters to indicate the several parts.

Figure 1 is an elevation of my novel starting mechanism as seen from the left in Fig. 2, the end plate being removed; Fig. 2 a view as seen from the right in Fig. 1, the upper portion being in central vertical section; Fig. 3 a section on the line 3—3 in Fig. 2 looking in the direction of the arrows; Fig. 4 a section on the line 4—4 in Fig. 3 looking in the direction of the arrows; and Fig. 5 is an elevation partly in section of the driving member detached, its position being substantially as seen from the left in Fig. 1.

10 denotes a shaft to which a driven member 11 is rigidly secured in any suitable manner, as by a key 12 and 13 a driving member mounted on the shaft contiguous to the driven member but free to rotate independently thereof. The driving member receives motion from driving rings 14 and 15, mounted to oscillate exteriorly thereof, and rollers 16 lying intermediate the driving rings and the driving member. Driving ring 14 is provided with an arm 17 and driving ring 15 is provided with an arm 18, both of which in use are moved in the same direction simultaneously in any suitable manner, as by means of links and a starting lever (not shown). At the outer end of the shaft is a hub 19 with which an end plate 20 has threaded engagement, said plate being provided with a ratchet 21 for en-

gagement by a starting crank which may be 55 slipped on over the hub should it be required to start the engine by "cranking up." The driven member is provided in its inner face with a recess 22 which receives a strong U-shaped spring 23, the purpose of which will 60 presently be explained, and with inwardly extending lugs 24 which extend through the driving member and lie between peripheral abutments 25 on said member. Between the forward walls of abutments 25 and the 65 rear walls of lugs 24 are recesses 26 which receive the rollers 16. The metal is removed at the bases of the forward walls of abutments 25 making the recesses deepest at that end and providing inclines 28, all 70 of which extend in the same direction from the deep portions of the recesses. The rollers lie between the inner walls of the driving rings and the inclines and when arms 17 and 18 are oscillated the rollers are caused 75 through the frictional engagement of the inner walls of the driving rings to travel up the inclines and wedge between the inclines and the walls. It will be noted that the driving rings are wholly independent of 80 each other, one acting to carry the driving member forward while the other is moving backward freely over it. In starting, motion is communicated to the driven member by means of a driving lug 29 which projects 85 laterally from the driving member into recess 22 in the driven member. The ends of spring 23 are outwardly turned and lie in an enlargement of the recess which is provided with a shoulder 30 and an abutment 31 90 in which is an adjusting screw 32. Lug 29 (see Fig. 3) lies between shoulder 30 and one of the outwardly turned ends of the spring, the other end of the spring bearing against the adjusting screw by which the 95 tension of the spring may be regulated.

When oscillatory motion is communicated to the driving rings, one of said rings will cause the rollers to travel up the inclines and wedge which will impart forward movement to the driving member, and, through the engagement of lug 29 with spring 23 (see Fig. 3) and the engagement of the other end of the spring with the adjusting screw in the abutment on the driven member, will communicate motion to the driven member and through said member to the shaft. The instant the power of an engine is

communicated to the shaft its rotation will be faster than the rotation of the driving member. In other words, the shaft will run away from the driving member and lugs 24 on the driven member will engage abutments 25 on the driving member which will be carried forward faster than the operative driving ring and disconnected therefrom as the rollers will necessarily drop back into the deep portion of the recesses, leaving the parts in the position shown in Fig. 1.

Should the engine backfire, the blow will be delivered through the adjusting screw to the spring, the first effect being to cause the spring to yield and the driven member to jump forward, lugs 24 striking the rollers and knocking them backward down the inclines, whereby the driving member is instantly disconnected from the driving rings.

Having thus described my invention I claim:

1. Starting mechanism comprising a driving member having a driving lug, a driven member having lugs by which the driving member is carried after the engine has started, a spring intermediate the driving lug and the driven member and means for imparting rotary movement to the driving member.

2. Starting mechanism comprising a driving member having a driving lug and peripheral recesses with inclines, driving rings outside the driving member, rollers between the inclines and the driving rings, a driven member having lugs engaging the driving member and a spring intermediate the driving lug and the driven member which receives the blow of a backfire.

3. Starting mechanism comprising a driving member having a driving lug and peripheral recesses with inclines, driving rings outside the driving member, rollers between the inclines and the driving rings, a driven member having lugs engaging the driving member and a recess having an abutment and a spring in said recess which bears against the abutment and against which the driving lug bears.

4. Starting mechanism comprising a driving member having a driving lug and peripheral recesses with inclines, driving rings outside the driving member, rollers between the inclines and the driving rings, a driven member having lugs engaging the driving member and a recess having a shoulder and an abutment, and a spring in the recess having outwardly turned ends, one of said ends engaging the abutment and the other being engaged by the driving lug.

5. Starting mechanism comprising a driving member having a driving lug and peripheral recesses with abutments and inclines, driving rings, rollers intermediate the

inclines and the rings, a driven member having lugs engaging the abutments and a spring intermediate the driving lug and the driven member, oscillation of the driving rings causing the rollers to travel up the inclines and rotate the driving member and the driving lug communicating motion to the driven member, increased motion of the driven member causing the lugs thereon to engage the abutments on the driving member and carry the latter forward leaving the rollers in the deep portions of the recesses, and a backfire causing the spring to yield and the lugs on the driven member to knock the rollers backward and disconnect the driving member from the driving rings.

6. Starting mechanism comprising a driving member having a driving lug and peripheral recesses with abutments and inclines, driving rings, rollers intermediate the inclines and the rings, a driven member having lugs engaging the abutments, and a spring having outturned ends, one of said ends engaging the driven member, the other being engaged by the driving lug.

7. The combination with a shaft and a driven member secured thereto and provided with lugs, of a driving member loose on the shaft and having a driving lug, abutments engaged by the lugs on the driven member and peripheral recesses with inclines, driving rings, rollers intermediate the inclines and the rings and a spring intermediate the driving lug and the driven member, whereby oscillation of the rings imparts rotary motion to the other parts and when the shaft turns faster than the driving member or turns backward, the driving member is disconnected from the rings.

8. The combination with a shaft and a driven hub secured thereto and provided with lugs, of a driving member loose on the shaft and having a driving lug, and abutments engaged by the lugs on the driven member, a spring intermediate the driving lug and the driven member, and means for imparting rotary movement to the driving member.

9. The combination with a driving member having a driving lug and peripheral recesses with inclines, driving rings, and rollers between the inclines and the rings, of a driven member having lugs engaging the driving member, and a spring intermediate the driving lug and the driven member, substantially as described for the purpose specified.

In testimony whereof I affix my signature in presence of two witnesses.

HUBERT MEREDITH-JONES.
